ANTENNA SYSTEM

Klaas Posthumus, Eindhoven, Netherlands, assignor, by mesne assignments, to Hartford National Bank and Trust Company, Hartford, Conn., as trustee

Application April 24, 1946, Serial No. 664,495
In the Netherlands October 2, 1942

Section 1, Public Law 690, August 8, 1946
Patent expires October 2, 1962

6 Claims. (Cl. 250—33.51)

1

In an antenna system comprising a conductor wherein solely travelling waves may appear, it is known that this conductor can be replaced, for avoiding the losses occurring in the necessary terminating resistance, by two juxtaposed parallel conductors which are arranged at a small distance from each other, say $\frac{1}{10}$ or less of the operating wave length, and are excited in such manner that stationary waves displaced in phase by 90° appear in them.

The present invention has for its object to provide an extremely suitable method of connecting and arranging the feed conductors in an antenna system comprising such a pair of conductors.

According to the invention, one conductor of the pair of conductors is interrupted at a current loop, which occurs at a point preferably midway the ends, and the connecting terminals thus formed are respectively connected to the conductors of a twin-core feed line, the other conductor being connected to a single-core feed conductor at the voltage loop which occurs at the point corresponding to the point of interruption.

In order to avoid radiation coupling between the two feed systems preferably the single-core feed conductor is provided midway between the conductors of the twin-core feed line.

The invention will be more fully explained by reference to the accompanying drawing representing, by way of example, an antenna system according thereto.

In the sole figure the reference number 1 designates a half-rhomb antenna located in a horizontal plane for the emission of oscillations to be transmitted mainly in the horizontal direction indicated by the arrow 2. The antenna is composed, in a manner known per se, of two juxtaposed parallel conductors 3, 3' and 4, 4' which are arranged at a small distance from each other so that they are strongly coupled by radiation. The conductors 3, 3' and 4, 4', each of which has a length of say 4λ (λ =operating wave length) should be excited in such manner that stationary waves displaced in phase by 90° appear therein.

The ends of the conductor 3, 3', in contradistinction to those of the conductor 4, 4', are earthed so that, since the length of the conductors is a whole multiple of the operating wave length, a current loop occurs at the middle of the conductor 3, 3', whereas a voltage loop occurs at the middle of the conductor 4, 4'.

The conductor 3, 3' is interrupted at the middle where it is connected to a feed line 5 consisting of two conductors, while the middle of the

2

conductor 4, 4' where a voltage loop occurs, is connected to a single-core feed conductor 6 provided between the conductors of the lead 5. The twin-core feed line 5 and the single-core feed conductor 6 are inductively coupled with coils 8 and 9 respectively which are connected to a transmitter 7 and to which are applied voltages displaced in phase by 90° .

In this way the conductor halves 3 and 3' are fed in push-pull, whereas the conductor halves 4 and 4' are fed in parallel with a phase displacement of 90° with respect to the conductor halves 3 and 3'.

What I claim is:

1. An antenna system comprising first and second radiating conductors juxtaposed in parallel relation and having respective lengths substantially equal to a whole multiple of the operating wave-length of the antenna system, said first conductor being divided at the midpoint thereof to provide input terminals thereto, said first conductor being directly grounded at both extremes thereof, and a transmission line for feeding said conductors and formed by three parallel wires, the outer wires of said line being connected to said input terminals and the intermediate wire of said line being connected to the midpoint of said second conductor.
2. An antenna system comprising first and second radiating conductors juxtaposed in parallel relation and having respective lengths substantially equal to a whole multiple of the operating wave-length of the antenna system, said first conductor being divided at the midpoint thereof to provide input terminals thereto, said first conductor being grounded at both extremes thereof, and a transmission line for feeding said conductors and formed by three parallel wires, the outer wires of said line being connected to said input terminals and the intermediate wire of said line being connected to the midpoint of said second conductor.
3. An antenna system comprising first and second radiating conductors juxtaposed in parallel relation and having respective lengths substantially equal to a whole multiple of the operating wave-length of the antenna system, said first conductor being divided at the midpoint thereof to provide input terminals thereto, said first conductor being grounded at both extremes thereof.

and a transmission line for feeding said conductors, said line being formed by three equi-spaced parallel wires, the outer wires of said line being connected to said input terminals and the center wire being connected to the midpoint of said second conductor.

4. An antenna system comprising first and second radiating conductors juxtaposed in parallel relation and having respective lengths substantially equal to a whole multiple of the operating wave-length of the antenna system, said first conductor being divided at the midpoint thereof to provide input terminals thereto, said first conductor being grounded at both extremes thereof, a transmission line for feeding said conductors, said line being formed by three equi-spaced parallel wires, the outer wires of said line being connected to said input terminals and the center wire being connected to the midpoint of said second conductor, means for applying radio frequency voltages of a predetermined wavelength and displaced 180° in phase from each other to the two outer wires of said line, and means for applying a radio frequency voltage of said wavelength and displaced 90° in phase from the voltages in the outer wires to the center wire of said line.

5. An antenna system adapted to be energized from a source of high frequency voltage having a predetermined wavelength, said system comprising first and second radiating conductors juxtaposed in parallel relation each having a total length substantially equal to a whole multiple of the operating wavelength of said system, said first conductor being divided at the midpoint thereof to provide input terminals thereto, said first conductor being directly grounded at the ex-

tremes thereof, a transmission line for feeding said conductors, said lines being formed by three parallel wires, the two outer wires of said line being connected to said input terminals and the intermediate wire being connected to the midpoint of said second conductor, a first transformer having a primary connected to the voltage source and a centertapped secondary whose ends are connected to said outer wires and whose center-tap is grounded, and a second transformer having a primary connected to the voltage source and a secondary having one end thereof connected to said intermediate wire and the other end thereof grounded.

10 6. An antenna system as set forth in claim 5 wherein the axes of said first and second parallel conductors are arranged in an oblique angle whose apex is the midpoints thereof whereby said conductors form a half-rhombic antenna.
